US00D579617S

(12) **United States Design Patent**
Malczewski et al.

(10) **Patent No.:** US D579,617 S
(45) **Date of Patent:** ** Oct. 28, 2008

(54) **RECYCLE CENTER**

(75) Inventors: **Edmund A. Malczewski**, Milwaukee, WI (US); **Casey M. Dembowiak**, Greenfield, WI (US)

(73) Assignee: **Riverwest Engineering & Design, Inc.**, Milwaukee, WI (US)

(**) Term: **14 Years**

(21) Appl. No.: **29/296,156**

(22) Filed: **Oct. 15, 2007**

(51) **LOC (8) Cl.** 09-09

(52) **U.S. Cl.** D34/1

(58) **Field of Classification Search** D34/1, D34/5, 6, 7, 8, 9, 10, 11; 220/908-913

See application file for complete search history.

(57) **CLAIM**

The ornamental design for a recycle center, as shown and described.

DESCRIPTION

FIG. 1 is an isometric view of a recycle center in accordance with the present invention;

FIG. 2 is a top plan view of the recycle center of FIG. 1;

FIG. 3 is a front elevational view of the recycle center of FIG. 1;

FIG. 4 is a bottom plan view of the recycle center of FIG. 1;

FIG. 5 is a side elevational view of a first side of the recycle center of FIG. 1;

FIG. 6 is a side elevational view of a second side of the recycle center of FIG. 1; and,

FIG. 7 is a rear elevational view of the recycle center of FIG. 1.

The broken line in the drawings is included for illustrative purpose only and forms no part of the claimed design.
